UNITED STATES PATENT OFFICE.

HENRY A. BURBANK, OF WESTFIELD, MASSACHUSETTS.

ROTARY HAND-STAMP.

SPECIFICATION forming part of Letters Patent No. 391,228, dated October 16, 1889.

Application filed July 5, 1887. Serial No. 243,325. (No model.)

To all whom it may concern:

Be it known that I, HENRY A. BURBANK, a citizen of the United States, residing at Westfield, in the county of Hampden and State of Massachusetts, have invented new and useful Improvements in Rotating Hand-Stamp, of which the following is a specification.

This invention relates to rotating hand-stamps, the object being to provide a stamp of this class of improved construction which is adapted to be used in connection with a suitable handle or to be applied to the end of a pencil for desk use, the pencil serving for the handle, an inking-pad being located in proximity to the type-wheel, whereby the stamp is self-inking; and the invention consists in the peculiar construction and arrangement of the stamp, all as hereinafter fully described, and pointed out in the claim.

In the drawings, forming part of this specification, Figure 1 is a perspective view of a hand-stamp embodying my improvements, a portion of the side of the type-wheel case being shown broken away, and in connection with this figure is shown the end of the finger of the operator applied in operative position to a spring-stop attached to the inner side of the type-wheel case. Fig. 2 is an elevation of the inner side of the type-wheel. Fig. 3 is an end view of the type-wheel case, which is shown partly in section, this figure disclosing in plan view the inking-pad and that portion of the inking-pad case in which it is located. Fig. 4 is an elevation of the periphery of the type-wheel. Fig. 5 is an elevation of the outer side of the type-wheel. Fig. 6 is a perspective view of the pivot-bolt of the type-wheel. Fig. 7 is a perspective view of a screw by which the pivot-bolt is secured to the type-wheel case.

In the drawings, 2 is the type-wheel case, of cylindrical form, constructed, preferably, of sheet metal and having one side open to provide for inserting therein the type-wheel. Said case 2 has secured to its inner side by one end a stop-spring, 13, having a headed pin, as shown, connected to its free end, which projects through the periphery of the type-wheel case in convenient position to permit the operator to place one finger on the head of said pin when he holds the stamp by the han-

dle 6. In the side of the type-wheel case is formed an oblong opening to receive the end of the type-wheel pivot-bolt 9, as shown in Fig. 1, a screw, 10, being adapted to be screwed into the said oblong-shaped end of the pivot-bolt, 9, whereby the latter is secured to the said case and is prevented from turning when the type-wheel is rotated thereon, as below described.

The type-wheel case 2 is rigidly-fixed by a portion of its border to the open end of the inking pad case 5, the portion of the border of the type-wheel case which is covered by the inking-pad case being cut away, so that when the inking pad 4, (see Fig. 3,) of felt or other similar soft absorbent material, is placed in the inking-pad case it presents an inked surface, with which the letters on the type-wheel are brought in contact when said wheel is rotated, whereby the letters are properly inked. The position, substantially, of said inking-pad 4 in the inking-pad case 5 is indicated by a curved dotted line on the side of said case in Fig. 1, and the exposed side of the inking-pad is shown in Fig. 3. A portion of the periphery and one side of said case has an opening formed therein, whereby the letters on the type-wheel are exposed, as shown in Fig. 1.

The type-wheel 3 consists of a flat metallic band, *v*, of suitable sheet metal, having rigidly secured to one edge thereof the disk *a*, which projects beyond the periphery of said band *v*. When said type-wheel is placed in the type-wheel case 2 in the position shown in Fig. 1, the said disk *a* constitutes one side of the type-wheel case, and its periphery *c* is milled or knurled, as shown in Fig. 1, so that when the stamp is moved over the surface of paper, or anything upon which it is desired to print the letters of the stamp, the type-wheel will be caused to rotate by the frictional contact of said milled periphery with the paper. Said type-wheel has fixed therein a stop-pin, 14, which is adapted to engage with the end of the aforesaid stop-spring 13 when the free end of the latter is forced inward toward said wheel by the operator, thereby stopping the type-wheel at a certain point in its revolution, for the purpose below described. The said disk *a*, as shown in Fig. 5, has also a stop-mark, *e*, thereon near its periphery, whereby the oper-

ator may see that the revolution of the type-wheel should be stopped at a certain point after the wheel has rotated sufficiently to print the matter on the wheel. The said stop-mark 5 *e* is only another means, in addition to the stop 13 and pin 14, for aiding the operator in arresting the rotation of the type-wheel at will; but neither of these means is essential in the 10 operation of the stamp, for a person who is accustomed to its use will give the stamp sufficient movement to print the name on the type-wheel with hardly a thought of said stopping devices or indicating-mark, the latter being plainly visible to the operator when using the 15 stamp, for the reason that in practice the side of the wheel-case covered by the disk *a* is before the operator while using the stamp. Instead of fixing said stop-pin in the type-wheel, a slight projection may be formed on the wheel 20 itself for the end of the stop spring 13 to engage with.

The letters of the stamp constituting the name or other matter which is to be printed by the use thereof (shown in Fig. 1) are made, 25 preferably, by constructing a rubber band, on which are formed, in the usual way, the desired letters or figures; but, if preferred, any suitable letters or figures of rubber or other material may be attached directly to or formed 30 upon the said metallic band *v*, which constitutes the face of the type-wheel. The aforesaid rubber band 12, having the stamp-letters thereon, is passed around the type-wheel, as illustrated in Figs. 1, 2, and 4, and its ends 35 are secured by a clamp-plate, 8, which is secured to the wheel by suitable screws between which and the side of the wheel the ends of said band are clamped.

By reference to Fig. 4, in which the projecting letters on the band 12 are indicated by dotted lines, it is seen that the said clamp-plate 8 covers a part of the space on the periphery of the wheel between the first and last letters on the said band, and in adjusting the 40 type-wheel to its proper operative position in the type-wheel case the type-wheel, after having been rotated to print from the matter thereon, is intended to be stopped by the operator when the said clamp-plate comes around 45

opposite the above-referred-to opening in the 50 periphery of the type-wheel case through which the printing-letters are exposed, and therefore when the operator uses the stamp he places the said open portion of the case against the paper, bearing gently thereupon and drawing it over the surface of the latter, thereby causing the type-wheel to rotate by the contact of the milled edge *c* with the paper, the lettering on the type-wheel to be moved over and against the inking-pad and to be rotated 55 in contact with the paper, thereby effecting the printing or stamping. During said operation the operator may or may not, at his pleasure, operate the stop-spring 13, as above described. By stopping the type-wheel, as 60 aforesaid, the printing characters are kept within the case 2 when the stamp is not used, and are protected from dust and dirt.

When the type-wheel is removed from the 65 case 2, the surface of the inking-pad 4 and the open end of the inking-pad case are clearly exposed, and the inking-pad may have ink easily applied thereto, or it may be replaced with a freshly-inked pad.

A ferrule, 7, is attached to the inking-pad 70 case 5 to receive the end of a handle, 6, when such a handle as is shown in Fig. 1 is used on the stamp; but a very convenient way of using the stamp, under many circumstances, is to attach it to the end of a common lead-pencil, 75 and when so used the said ferrule is made of a greater length than that shown in Fig. 1, and the size of the stamp is adapted to said pencil use.

What I claim as my invention is—

In a hand-stamp, the type-wheel case 2, having one side open and an opening through its periphery, combined with the type-wheel 3, journaled in said case and consisting of the disk *a* and the circular band *v*, secured by one 80 edge thereof to said disk, which constitutes one side of said case, and suitable letters attached to said wheel, substantially as set forth.

HENRY A. BURBANK.
